ELECTRICAL BLOCK TRAIN-STOPPAGE AND SIGNAL-SETTING SYSTEM.

1,312,249.

Specification of Letters Patent. Patented Aug. 5, 1919.

Application filed August 2, 1918. Serial No. 247,913.

To all whom it may concern:

Be it known that I, BUTLER J. HASKINS, a citizen of the United States, residing at Kansas City, in the county of Jackson and 5 State of Missouri, have invented certain new and useful Improvements in Electrical Block Train-Stoppage and Signal-Setting Systems, of which the following is a specification.

This invention relates to electrical block train stoppage and signal setting systems, and the object is to produce a closed circuit system whereby the electrical connection of the rail members of the block by the entrance of a train into such block or the breaking of 10 a rail, shall, in addition to setting the semaphores protecting such block, as common, effect the application of the brakes on a following train and prevent it from entering the occupied block.

With this general object in view, the invention consists in certain novel and useful features of construction and organization of parts as hereinafter described and claimed; and in order that it may be fully understood 25 reference is to be had to the accompanying drawing, in which:

Figure 1, is a diagrammatic view of a section of railway track equipped with an electrical system embodying the invention.

Fig. 2, is a diagrammatic side view showing the operative relation between the track system and the electrical equipment to cooperate therewith which is carried by a train.

In the said drawing, A, B, and C represent three blocks of a railway track, of each of which 1 and 2 represent the rails and 3 the insulation between adjacent blocks. 4 and 5 indicate conductors of an ordinary or 35 any preferred type of track circuit for the 40 operation of semaphores or the like, not shown.

Referring now to the novel features of the invention, 6 indicates a solenoid located at 45 a suitable point in each block and electrically connected by conductors 7 and 8 to the rails of the block in advance. The core 9 of said solenoid is normally held by the energization of the latter in electrical 50 contact with a pair of conductors 10 and 11 respectively connected to conductors 12 and 13 connecting a pair of coils 14 and 15 arranged in any suitable manner between the track rails. Said coils are respectively pro-

tected by housings 16 and 17, and the former is equipped with an inclined guard 18 at the end from which the approach of a train T occurs, in order that any loose part depending low enough to strike the coil, may encounter the guard and be deflected upwardly 55 thereby. From the foregoing taken in connection with the drawing, it will be apparent that when a train leaves one block and enters another, it shunts the track circuit (through the wheels and axle) from the solenoid in 60 the block just passed to permit the core 9 of said solenoid to drop and thereby break the connection between conductors 10 and 11; and thus leave the coils 14 and 15 of the said 65 unoccupied or passed block susceptible to 70 energization in a manner hereinafter explained.

Mounted upon each train is the following equipment; 19 and 20 are coils, the former normally energized, supported beneath the 75 engine in such position that they shall pass over coils 14 and 15, so that the magnetic field of coil 19 shall inclose coil 14 at the moment coil 20 is above coil 15. If at this 80 time the block ahead is not occupied by a train nor the rails of said block otherwise electrically connected, or a rail displaced or broken, the coil 14 will be unaffected because the solenoid of the same block is energized and the core thereof consequently engaged 85 with the adjacent contacts 10 and 11. On the other hand, if the rails of the block ahead are connected by a train or otherwise, and are intact, the circuit between coils 14 and 15 is not shorted, hence the proximity 90 of coil 19 to coil 14 produces an induced current through coils 14 and 15, the energization of the latter energizing the coil 20—at the time just above coil 15—for a 95 purpose hereinafter explained. Magnets 19 and 20 are preferably provided with housings 21 and 22 corresponding to housings 16 and 17 if desired, and housing 22 is equipped with an upwardly and forwardly inclined guard 23 to perform the same function for coil 20 as the guard 18 performs for coil 14.

Coil 19 is connected by a conductor 24 to a dynamo 25 on the engine, and the latter is connected by a conductor 26 through a magnet 27 and conductor 28, to a movable contact or lever 29 held normally by a retractile spring 30 against a contact 31, connected by

a conductor 32 to the coil 19. This circuit is normally closed so that coil 27 may hold the armature 33 attracted, said armature being mounted upon a lever 34 for holding a weighted arm 35 in elevated position. The weighted arm is to operate a valve 36 of any suitable type controlling the air brake line 37 of the train, and to release said arm to effect the operation of the brakes, (not shown), of the train, retractile spring 38 is connected to lever 34 to trip the same from the weighted arm when the circuit through the dynamo is broken.

Arranged adjacent movable contact or lever 29 and an armature 40 carried thereby, is a magnet 39 electrically connected by conductors 41 and 42 to the coil 20. From the foregoing, it will be seen that when one block is occupied by a train and therefore effects a break in the circuit through the solenoid 6 in the block to the rear of the occupied block, the short circuit through coil 14 established by conductors 10 and 11 and core 9 is broken, assuming that a train is in block B, it will be seen that when the coils 19 and 20 of a train in block A are respectively in superposed relation with coils 14 and 15, a current will be induced by coil 19, through coils 14 and 15, and by the latter a current will be induced through coil 20, conductors 41 and 42, and electromagnet 39, and this current energizes magnet 39, which attracts its armature 40 and breaks the circuit through magnet 27 between lever 29 and contact 31. The break in the circuit from the dynamo is, of course, instantly followed by the tripping of the weighted arm and the operation of the brake mechanism of the train so that it cannot enter the next block until the same is vacated or otherwise cleared.

It will be apparent that the shunting of a solenoid out of circuit in one block may, as hereinbefore suggested, occur through the fall of a bridge, the displacement of a rail or the connection of the rails by a wire in the next block ahead.

From the above description it will be understood that the embodiment of the invention may be in various forms as regards its form, detail construction and organization of parts, without departure from the principle of construction shown or the scope of the appended claims.

55 I claim:

1. In an electric block system for railways, a pair of electrically connected coils located within each block, means for normally preventing flow of current through said coils simultaneously, and means actuated by the electrical connection or a break in one of the rails of the block in advance of the block containing such coils, for making the latter coils susceptible to simultaneous energization.

2. In an electric block system for railways, a pair of electrically connected coils located within each block, means for normally preventing flow of current through said coils simultaneously, means actuated by the electrical connection or a break in one of the rails of the block in advance of the block containing such coils for making the latter coils susceptible to simultaneous energization, and means carried by a train in the same block as that in which the coils are located for inducing a flow of current through said pair of coils when susceptible to such influence.

3. In an electric block system for railways, a pair of electrically connected coils located within each block, means for normally preventing flow of current through said coils simultaneously, means actuated by the electrical connection or a break in one of the rails of the block in advance of the block containing such coils for making the latter susceptible to simultaneous energization, means carried by a train in the same block as that in which the magnets are located, for inducing a flow of current through said pair of coils when susceptible to such influence, operative mechanism carried by the train, and means whereby the induction of current through said pair of coils simultaneously shall effect operation of said mechanism.

4. In an electric block system for railways, a pair of electrically connected coils located within each block, means for normally preventing flow of current through said coils simultaneously, means actuated by the electrical connection or a break in one of the rails of the block in advance of that block containing the coils for making the latter coils susceptible to simultaneous energization, means carried by a train in the same block as that in which the coils are located, for inducing a flow of current through said pair of coils when susceptible to such influence, an automatic valve on the train, means holding said valve in a predetermined position, and means actuated by the flow of current in said coils for tripping said holding means.

5. In an electric block system for railways, a pair of electrically connected coils located within each block, means for normally preventing flow of current through said coils simultaneously, means actuated by the electrical connection or a break in one of the rails of the block in advance of the block containing such coils, for making the latter susceptible to simultaneous energization, means carried by a train in the same block as that in which the coils are located, for inducing a flow of current through said pair of coils when susceptible to such influence, a valve-controlling magnet carried by the train and train-carried means

actuated by the flow of current through said coils to effect the deenergization of said coils.

6. In an electric block system for rail-ways, a pair of electrically connected coils located within each block, means for normally preventing flow of current through said coils simultaneously, means actuated by the electrical connection or a break in one of the rails of the block in advance of the block containing such coils, for making the latter susceptible to simultaneous energization, a train-carried coil in a closed circuit and adapted as carried over one of said pair of coils to set up an electrical current by induction through said pair of electrically connected coils, an operative mechanism carried by the train, a magnet in the said circuit for holding said mechanism inoperative, and means actuated by the energization of the first-named pair of coils by induction, to break the circuit through the train-carried coil and effect the operation of said operative mechanism.
7. In an electric block system for rail-ways, a pair of electrically connected coils located within each block, means for normally preventing flow of current through said coils simultaneously, means actuated by the electrical connection or a break in one of the rails of the block in advance of the block containing such coils, for making said coils susceptible to simultaneous energization, a train-carried coil in a closed circuit and adapted as carried over one of said pair of coils to set up an electrical current by induction through said pair of electrically connected coils, an operative mechanism carried by the train, a magnet in the said circuit for holding said mechanism inoperative, a second coil carried by the train, an electromagnet in circuit with the last-named train-carried coil and an armature for the last-named magnet; said last-named magnet being energized to attract its armature and break the circuit through the first-named train-carried coil to effect operation of said operative mechanism, when a current is established in the second train-carried coil by induction from the induced current in the said first-mentioned pair of coils.

8. In an electric block system for rail-ways, a pair of electrically connected track rails located in each block, a pair of electro-

magnetic devices for and in circuit with the track rails of each block but located within an adjacent block to the rear, means for normally preventing simultaneous energization of said devices, and means whereby said first-named means shall be rendered inoperative to prevent simultaneous energization of said devices.

9. In an electric block system for rail-ways, a pair of electrically connected coils located within each block, means for normally preventing flow of current through said coils simultaneously, and means actuated by the electrical connection or a break in one of the rails of the block in advance of the block containing such coils, for freeing said coils for simultaneous energization, in combination with a pair of coils carried by a train and adapted to be respectively disposed adjacent said first pair of coils, one of the train-carried coils being always energized and adapted when the first-named coils are free for simultaneous energization to induce a flow of current through said first-named coils, and means actuated by a current induced in the other of said train-carried coils by the simultaneous flow of current in the first-named pair of coils, for effecting the deenergization of the normally energized train-carried coil.

10. In an electric block system for rail-ways, a pair of coils carried by a train, one of said coils being in a closed circuit also including an electromagnet, and the other coil in a circuit with a second electromagnet; the armature of said last-named electromagnet serving when attracted, to break said closed circuit.

11. In an electric block system for rail-ways, a pair of coils carried by a train, one of said coils being in a closed circuit also including an electromagnet, and the other coil in a circuit with a second electromagnet; the armature of said last-named electromagnet serving when attracted, to break said closed circuit, an automatic valve, movable means caused by the electromagnet of the closed circuit to retain the valve in one position, and means for operating said movable means when the closed circuit is broken, to trip the valve retaining means from its retaining position.

In testimony whereof I affix my signature.

BUTLER J. HASKINS.
